UNITED STATES PATENT OFFICE

ERNEST RIDGILL, OF SHEFFIELD, ENGLAND

JIGGER CONVEYER

Application filed March 28, 1931, Serial No. 526,064, and in Great Britain June 24, 1930.

This invention is for improvements in or relating to jigger conveyers and more particularly to mechanism arranged to impart reciprocatory movement to the troughs of such conveyers.

Mechanisms of this character usually comprise a crank arranged to be rotated at a uniform speed and which is coupled to the trough of the conveyer by a connecting rod or link mechanism which modify the rectilinear movements of the trough in both the forward and backward strokes thereof from the simple harmonic motion derived from uniform rotational movement of the crank so as to effect a relatively more rapid reversal of motion of the trough at the end of the forward stroke than at the end of the rearward stroke. This motion of the trough of the conveyer produces the conveying action.

The present invention provides a mechanism which imparts reciprocatory motion to the troughs of jigger conveyers which produces an improved conveying action as compared with that above described and whilst the reversal of motion imparted to the trough of the mechanism at each forward end of the stroke thereof, is relatively much more rapid than the reversal of motion at the end of each return stroke thereof, the motion of the trough during the return stroke conforms substantially to simple rectilinear movement derived from uniform rotational movement, that is to say, to simple harmonic motion.

It is found that motion imparted in accordance with this invention to the trough of a jigger conveyer during the return stroke thereof, whilst the material in the trough is moved relatively to the trough in a forward direction, gives an improved conveying action over known constructions and enables a conveyer mechanism to be run at relatively much slower speeds than heretofore.

In order that the invention may be fully understood, reference is directed to the accompanying drawings, in which:

Figure 1 is a longitudinal section of a mechanism constructed in accordance with the invention,

Figure 2 is a plan of Figure 1 with portions of the driving mechanism broken away and

with the cover plate of the mechanism illustrated in Figure 1 removed.

Figure 3 is a sectional end view on the line 3—3 of Figure 2,

Figure 4 is a plan view of a portion of a modified form of mechanism to that illustrated in Figure 2,

Figure 5 is a section on the line 5—5 of Figure 4,

Figure 6 is a section on the line 6—6 of Figure 4, and

Figures 7 and 8 are graphs illustrating the rectilinear motion produced by the mechanisms illustrated in Figures 1 to 6.

Referring to Figures 1 to 3, a casing 1 provided with a cover plate 2 is mounted upon skid members 3 in the manner described in the specification of patent application No. 28627 of 1930. A driving mechanism 4, indicated in Figure 2 in outline only, is bolted to the casing 1 and is arranged to rotate a crank shaft 5 mounted in bearings 6 and 7 provided in the casing 1 at a uniform speed. The crank pin 8 of the crank shaft 5 is connected by a connecting rod 9 to a pin 10 carried by one arm 11 of the bifurcated double armed lever 11, 12 which is rotatably mounted on trunnions 13 in bearings 13a carried by the casing 1. The connecting rod 9 is provided with a cut-away portion 14, Figure 1, to permit the parts of the mechanism to assume the position indicated in Figure 1, in which position the cutaway portion 14 is arranged to clear the central portion of the pivot forming the trunnions 13 of the double armed lever 11, 12. The arm 12 of the double armed lever is provided with a pin 15 which is connected by a connecting rod 16 to a pin 17 mounted upon a slide block 18. The slide block 18 is mounted in guides 19 so as to be slidable in a longitudinal direction. A pin 20, mounted on the slide block 18, is connected by a link 21 to a crank pin 22 provided upon a crank shaft 23 mounted in bearings 24 provided in the casing 1.

The crank shaft 23 is arranged to extend beyond one side of the casing 1 and is mounted at its free end in a bearing 25 which is secured to one of the skid members 3 and to the driving mechanism 4.

A pair of bifurcated arms 26, 27 are keyed to the crank shaft 23 between the casing 1 in the bearing 25 in the manner indicated in Figures 1 and 2. The free ends of the arms 26, 27 are each provided with two holes 28, 29 arranged in radial alignment along the arms. A pin 30 is located in the holes 29 of each of the arms 26, 27 so as to connect a link 31 to each of the said arms. The other end of each of the links 31 is provided with a horizontally disposed rectangular hole through which a bar 32, rectangular in cross-section, is arranged to extend, the said bar being locked to the links 31 by means of bolts 33. The bar 32 extends beyond the link 31 which is connected to the arm 27 and is connected by a pin 34 to one end of a connecting rod 35, the other end of which is arranged to be connected by a pin 36 to the side of a trough of a jigger conveyer, not shown.

It is to be observed that the bar 32 may be arranged to extend upon the opposite side of the links 31, if required, to that illustrated in the drawings so that a conveyer trough may be driven from the opposite side of the mechanism. Further it will be appreciated that the pins 30 may be arranged to connect the links 31 to the arms 26, 27 by engagement with the holes 28 in lieu of the holes 29, thus affecting a slightly shorter stroke of the conveyer trough.

In the modification of the apparatus illustrated in Figures 4 to 6, the arms 27 on the shaft 23 are connected by a link 31 and pin 37 to a swivel connection comprising two articulated members 38, 39 connected together by means of a pin 40. The member 39 is connected by means of a pin 41 to one end 42 of a horizontally disposed double armed lever 42, 43. The lever 42, 43 is pivotally mounted upon a pin 44 provided with a shoulder 45 (Figures 2 and 6) from which two pegs 46 extend in a downward direction and are arranged to be located in corresponding holes 47 formed in one of the skid members 3. The lever 42, 43 is maintained in place upon the pin 44 by a U-shaped strap 48 secured to the skid member 3 by bolts 49. The strap 48 also maintains the pin 44 in position. The arm 43 of the lever 42, 43 is connected by a pin 50 to one end of a link 51, the other end of which is connected by a pin 52 to a connecting rod 53. The connecting rod 53 is arranged to be coupled to the underside of a conveyer trough (not shown) by means of a pin 54.

This arrangement permits the trough to be driven from the centre thereof and is in some cases preferable to the arrangement of the drive at the side of the trough as disclosed in Figures 1 to 3.

If it is required to drive a trough upon the opposite side of a mechanism to that effected with the arrangement of the mechanism shown in Figures 4 to 6, the pin 44 is secured

to the opposite side of the skid member 3 where a second set of holes 55 to receive the bolts 49 and a pair of holes 56 to receive the pegs 46 are provided. The relative positions of the link 31 and members 36, 39 and the link 51 and connecting rod 53 are reversed so that the link 31 is connected to the arm 26 on the shaft 23.

In all the constructions illustrated in the drawings, anchor plates 57 are provided on the skid members 3 to enable the lower end of pit props to be located therein for the purpose of securing the mechanism on the floor of a mine.

In the operation of the mechanism the crank shaft 5 is rotated at a uniform speed by the mechanism 4 as stated above in the direction of the arrow in Figure 1. The parts of the mechanism are illustrated in the drawings in a position which corresponds to the extreme forward limit of movement of the conveyer trough at which point during the normal working of the mechanism a relatively much more rapid reversing movement of the trough is effected than at the opposite limit of movement thereof.

The operation of the mechanism will be described with reference to the graphs shown in Figures 7 and 8 and is as follows:

The co-ordinate OX in each of the graphs indicates in degrees the uniform rotation of the crank shaft 5 and the co-ordinate OY indicates the rectilinear movement of the conveyer trough, the distance A—B in Figure 7 indicating the forward stroke, and the distance B—C indicating the return stroke. The straight line A, D, E, corresponds to a uniform velocity of the conveyer trough for both the forward and return strokes. The dotted line F indicates the velocity the trough would have if its motion corresponded to simple harmonic motion. The full line G indicates the velocity of the trough as produced by a uniform rotation of the crank shaft 5 in the mechanism illustrated in Figures 1 to 6. The graph in Figure 7 indicates the velocity of the trough during successive forward and return strokes, whilst the graph in Figure 8 indicates the velocity of the said trough during successive return and forward strokes. It will be observed from a study of the two graphs that the reversal of movement between the forward and return strokes as indicated at the point D in Figure 7 is relatively much more rapid than the reversal of movement between the return and next forward stroke which is indicated at the point E in Figure 8.

During a complete cycle of operation of the mechanism it will be observed from the graphs that during a forward stroke (that is, when the conveyer and material are moving together) an acceleration of the trough is produced which is initially much slower than would be the case if it were moved in a simple

harmonic motion. The trough is then accelerated into a substantially uniform speed which is maintained for a relatively large portion of the forward stroke. Towards the end of the forward stroke the trough is retarded at a relatively much greater rate than would be the case with the simple harmonic motion aforesaid, and this relatively rapid change of velocity is continued during the first small portion of the return stroke after which the return stroke conforms substantially to simple harmonic motion.

It is to be observed that the position of the parts of the mechanism indicated in Figures 1 to 6, corresponds to the position which the conveyer trough would have at the point D in Figure 7.

The reciprocatory motion produced by the mechanism above described results in a movement of the trough of the conveyer which causes the material in the trough to be carried forward therewith but the rapid reversal of movement at the end of the said forward movement of the trough causes the material, due to its inertia, to remain substantially in the forward position while the trough moves through its return stroke, the velocities of the trough during the return stroke being such as to enhance the conveying action to a considerable extent. At the end of the return stroke the gradual reversal of motion and the prolonged period during which this reversal is effected causes the material to settle in the trough and to be carried forward thereby during the next forward stroke.

With mechanisms illustrated in the drawings suitable dimensions for the parts thereof are as follows:—

Referring to Figure 1, the crank shaft 5 is arranged to produce a stroke of $8\frac{1}{4}$ ". The axis of the crank shaft 5 is disposed upon the same horizontal centre line as the axis of the trunnions 13 and is separated therefrom by a distance of 15". The axis of the pins 10 and 15 is each spaced at a distance of $5\frac{1}{4}$ " from the axis of the trunnions 13 and are located upon a line extending through the axis of the trunnions and the axis of both pins. The length of the connecting rod 9 between centres is $15\frac{1}{2}$ ". The length of the connecting rod 16 between centres is $8\frac{3}{4}$ ". The axis of the pin 17 is disposed at a distance of 4" below the axis of the trunnions 13 and crank shaft 5 whilst the pin 20 is spaced in a horizontal direction at a distance of 14". The axis of the pin 20 is disposed at a distance of $5\frac{3}{4}$ " below the axis of the crank shaft 5. The link 21 has a length of $26\frac{3}{8}$ " between centres and the crank pin 22 is spaced from the crank shaft 23 by a distance of $6\frac{1}{2}$ ". The holes 28 in the arm 26, 27 have a radial distance from the axis of the shaft 23 of $5\frac{1}{4}$ ", whilst the corresponding radial distance of the holes

29 is $7\frac{1}{2}$ ". It is to be observed that the radial line passing through the axis of the shaft 3 and centres of the holes 28, 29 is offset in a clockwise direction from the radial line through the pin 22 by a distance of $\frac{3}{8}$ " or about an angle of 3° in a clockwise direction at the centre of the pin 22. The radial line through the pin 22 is indicated at A in Figure 1 whilst the radial line passing through the holes 28, 29 is indicated at B, Figure 1. The length of the links 31, Figures 1 and 2, is 2 feet between centres, but it is to be observed that this dimension is not material to the particular embodiment of the invention illustrated.

In the arrangement illustrated in Figures 4 to 6, the distance from the centres of the pin 30 in the arm 27 and the pin 41 is 2 feet when the link 31 and articulated members 38, 39 are arranged in alignment with one another in the fully extended position thereof and the distance between the centres of each of the pins 41, 50 and the centre of the pin 44 is $20\frac{3}{8}$ ".

It will be understood that the dimensions given above are merely indicative of the relative proportions of the mechanism which give the best results in practice in accordance with the invention.

It is to be understood that numerous modifications may be made in the arrangement of the parts of the mechanism in accordance with this invention so long as the motion imparted to the conveyer trough conforms to that above described.

It will be appreciated that with the constructions of mechanism illustrated in the drawings, it is possible for the conveyer trough to be disposed relatively very close to either side of the mechanism, thus ensuring that a minimum space is required for the conveyer plant.

Further, it will be appreciated that by the provision of the crank shaft 23 to form an operative connection between the driving mechanism and the conveyer trough, it is possible for the casing 1 to be completely sealed and for the parts disposed therein to operate in an oil bath. This is a particularly important feature when conveyers are employed in mines as it prevents the access of dust to the bearings of the mechanism and, therefore, materially prolongs the useful life thereof.

It will be observed from Figure 3 that a skid member 3 is provided which is of considerably greater width than the skid members illustrated in Figures 1 to 3. This enables a larger number of anchor plates 57 to be provided on the said skid member which may, therefore, be maintained in place upon the floor of the mine by a correspondingly greater number of pit props, thus providing a relatively much more rigid anchorage.

for the pin 44 upon which the entire thrust of the trough of the conveyer is imposed.

I claim:

1. Mechanism for imparting reciprocatory motion to the troughs of jigger conveyers which comprises a driving crank coupled by a connecting rod to one arm of a pivotally mounted double-armed lever, the other arm of which is connected to a second connecting rod arranged to be operatively connected to the trough of a jigger conveyer, both said connecting rods being disposed at acute angles to the respective arms of said double-armed lever when the mechanism is in a position corresponding to the extreme forward limit of movement of the trough.

2. Mechanism for imparting reciprocatory motion to the troughs of jigger conveyers which comprises a crank coupled by a connecting rod to one arm of a pivotally mounted double-armed lever, the other arm of which is coupled by a second connecting rod to a slide block arranged to be operatively connected to the trough of a jigger conveyer, both said connecting rods being disposed at acute angles to the respective arms of said double-armed lever and the second rod at an acute angle to the direction of movement of said slide block when the mechanism is in a position corresponding to the extreme forward limit of movement of the trough.

3. Mechanism for imparting reciprocatory motion to the troughs of jigger conveyers which comprises an oil-tight casing, a driving crank disposed within said casing and the shaft of which is mounted in and extends through a bearing formed in a wall of the said casing, a connecting rod coupling said crank to one arm of a pivotally mounted double-armed lever, the other arm of which is coupled by a second connecting rod to a slide block, a link connecting said slide block to a second crank, the shaft of which is carried in and extends through at least one bearing provided in the walls of said casing and at least one arm on said second crank shaft located exteriorly of said casing for operatively connecting the mechanism to the trough of a jigger conveyer, and wherein the aforesaid connecting rods are disposed at acute angles to the respective arms of the double-armed lever and the second connecting rod at an acute angle in the direction of movement of the slide block when the mechanism is in a position corresponding to the extreme forward limit of movement of the trough.

4. Mechanism for imparting reciprocatory motion to the troughs of jigger conveyers which comprises an oil-tight casing, a driving crank disposed within said casing and the shaft of which is mounted in and extends through a bearing formed in a wall of the said casing, a connecting rod coupling said crank to one arm of a pivotally mounted double-

armed lever, the other arm of which is coupled by a second connecting rod to a slide block, a link connecting said slide block to a second crank, the shaft of which is carried in and extends through at least one bearing provided in the walls of said casing and at least one arm on said second crankshaft located exteriorly of said casing for operatively connecting the mechanism to the trough of a jigger conveyer, and wherein the aforesaid connecting rods are disposed at acute angles to the respective arms of the double-armed lever and the second connecting rod at an acute angle to the direction of movement of slide block and the said link at an acute angle to the second crank when the mechanism is in a position corresponding to the extreme forward limit of movement of the trough.

5. Mechanism for imparting reciprocatory motion to the troughs of jigger conveyers which comprises a driving crank, a connecting rod coupling said crank to one arm of a pivotally mounted double-armed lever, the other arm of which is coupled by a second connecting rod to a slide block, a link connecting said slide block to a second crank, a pair of arms on said second crankshaft, one of a pair of coupling rods secured at one end to each of said pair of arms, and a bar member reversably mounted at the other ends of said coupling rods, so that it may be arranged to extend upon either side thereof and means for connecting said bar member to the trough of a jigger conveyer, and wherein both the aforesaid connecting rods are disposed at acute angles to the respective arms of the double-armed lever and the second connecting rod at an acute angle to the direction of movement of the slide block when the mechanism is in a position corresponding to the extreme forward limit of movement of the trough.

6. Mechanism for imparting reciprocatory motion to the troughs of jigger conveyers which comprises an oil-tight casing, a driving crank disposed within said casing and the shaft of which is mounted in and extends through a bearing formed in a wall of the said casing, a connecting rod coupling said crank to one arm of a pivotally mounted double-armed lever, the other arm of which is coupled by a second connecting rod to a slide block, a link connecting said slide block to a second crank, the shaft of which is carried in and extends through at least one bearing provided in the walls of said casing, a pair of arms on said second crankshaft located exteriorly of said casing, one of a pair of coupling rods secured at one end to each of said pair of arms, and a bar member reversably mounted at the other ends of said coupling rods, so that it may be arranged to extend upon either side thereof and means for connecting said bar member to the trough of a jigger conveyer, and wherein both the aforesaid connecting rods are disposed at acute

angles to the respective arms of the double-armed lever and the second connecting rod at an acute angle to the direction of movement of the slide block when the mechanism is in a position corresponding to the extreme 5 forward limit of movement of the trough.

7. Mechanism for imparting reciprocatory motion to the troughs of jigger conveyers which comprises a driving crank, a connecting rod coupling said crank to one arm of a pivotally mounted double-armed lever, the other arm of which is coupled by a second connecting rod to a slide block, a link connecting said slide block to a second crank, at 10 least one arm on said second crank shaft, an operative connection between the said arm and one arm of a pivotally mounted double-armed lever, the other arm of which is arranged to be connected to the trough of a conveyer and means whereby the last said double-armed lever may be mounted upon the mechanism so as to extend upon either side thereof, and wherein both the aforesaid connecting rods are disposed at acute angles to the 15 respective arms of the first said double-armed lever and the second connecting rod at an acute angle to the direction of movement of the slide block when the mechanism is in a position corresponding to the extreme forward limit of movement of the trough.

8. Mechanism for imparting reciprocatory motion to the troughs of jigger conveyers which comprises an oil-tight casing, a driving crank, disposed within said casing and the shaft of which is mounted in and extends through a bearing formed in a wall of the said casing, a connecting rod coupling said crank to one arm of a pivotally mounted double-armed lever, the other arm of which is coupled by a second connecting rod to a slide block, a link connecting said slide block to a second crank, the shaft of which is carried in and extends through at least one bearing provided in the walls of said casing and at 20 least one arm on said second crankshaft, located exteriorly of said casing, an operative connection between the said arm and one arm of a pivotally mounted double-armed lever, the other arm of which is arranged to be connected to the trough of a conveyer and means whereby the last said double-armed lever may be mounted upon the mechanism so as to extend upon either side thereof, and wherein both the aforesaid connecting rods are disposed at acute angles to the 25 respective arms of the first said double-armed lever and the second connecting rod at an acute angle to the direction of movement of the slide block when the mechanism is in a position corresponding to the extreme forward limit of movement of the trough.

9. Mechanism for imparting reciprocatory motion to the troughs of jigger conveyers which comprises an oil-tight casing, a driving crank disposed within said casing and the shaft of which extends through a bear-

ing provided in a wall of said casing, a connecting rod coupling said crank to one arm of a pivotally mounted double-armed lever, the other arm of which is connected to a second connecting rod, and an operative connection extending through said casing between said second connecting rod and means for connection to the trough of a jigger conveyer and wherein both said connecting rods are disposed at acute angles to the respective 70 arms of said double-armed lever when the mechanism is in a position corresponding to the extreme forward limit of movement of the trough.

10. In a mechanism for imparting reciprocatory motion to the troughs of jigger conveyers the combination of the following parts having substantially the relative dimensions specified:—a driving crank having a stroke of 8.25 units coupled by a connecting rod of 85 15.5 units to one arm of a pivotally mounted double-armed lever, each arm of which is 5.25 units, the distance between centres of the crankshaft and the pivot of the double-armed lever being 15 units, and a second connecting rod connected to the other arm of said lever and arranged to be operatively connected to the trough of a jigger conveyer, both said connecting rods being disposed at 90 acute angles to the respective arms of said lever when the mechanism is in a position corresponding to the extreme forward limit of movement of the trough.

11. In a mechanism for imparting reciprocatory motion to the troughs of jigger conveyers the combination of the following parts having substantially the relative dimensions specified:—a driving crank having a stroke of 8.25 units coupled by a connecting rod of 100 15.5 units to one arm of a pivotally mounted double-armed lever, each arm of which is 5.25 units, the distance between centres of the crankshaft and the pivot of the double-armed lever being 15 units, and a second connecting rod 8.75 units long connecting the 105 other arm of said double-armed lever to a slide block adapted for connection to the trough of a jigger conveyer, both said connecting rods being disposed at acute angles to the respective arms of the double-armed 110 lever and the second connecting rod at an acute angle to the direction of movement of the slide block when the mechanism is in a position corresponding to the extreme forward limit of movement of the trough.

12. Mechanism for imparting reciprocatory motion to the troughs of jigger conveyers which comprises a driving crank, having a stroke of 8.25 units, a connecting rod 15.5 units long coupling said crank to one arm 120 5.25 units long of a pivotally mounted double-armed lever, the other arm 5.25 units long of which is coupled by a second connecting rod 8.75 units long to a slide block, a link 125 26.375 units long connecting said slide block 130

to a second crank of 6.5 units radius, a pair of arms 5.25 units long on said second crank-shaft, one of a pair of coupling rods secured at one end to each of said pair of arms, and a bar member reversably mounted at the other ends of said coupling rods, so that it may be arranged to extend upon either side thereof and means for connecting said bar member to the trough of a jigger conveyer, and wherein both the aforesaid connecting rods are disposed at acute angles to the respective arms of the double-armed lever and the second connecting rod at an acute angle to the direction of movement of the slide block when the mechanism is in a position corresponding to the extreme forward limit of movement of the trough.

18. Mechanism for imparting reciprocatory motion to the trough of jigger conveyers which comprises a driving crank having a stroke of 8.25 units, a connecting rod 15.5 units long coupling said crank to one arm 5.25 units long of a pivotally mounted double-armed lever, the other arm 5.25 units long of which is coupled by a second connecting rod 8.75 units long to a slide block, a link 26.375 units long connecting said slide block to a second crank of 6.5 units radius, at least one arm 5.25 units long on said second crankshaft, an operative connection between the said arm and one arm 20.375 units long of a pivotally mounted double-armed lever, the other arm 20.375 units long of which is arranged to be connected to the trough of a conveyer and means whereby the last said double-armed lever may be mounted upon the mechanism so as to extend upon either side thereof, and wherein both the aforesaid connecting rods are disposed at acute angles to the respective arms of the first said double-armed lever and the second connecting rod at an acute angle to the direction of movement of the slide block when the mechanism is in a position corresponding to the extreme forward limit of movement of the trough.

In testimony whereof, I affix my signature.

ERNEST RIDGILL.
